The ornamental design for a catheter handle with surface ornamentation, as shown and described.

DESCRIPTION

FIG. 1 is a rear top right perspective view of a catheter handle with surface ornamentation, showing our new design;

FIG. 2 is a front bottom left perspective view thereof;

FIG. 3 is a right side view thereof;

FIG. 4 is a left side view thereof;

FIG. 5 is a front side view thereof;

FIG. 6 is a rear side view thereof;

FIG. 7 is a top side view thereof; and,

FIG. 8 is a bottom side view thereof.

The broken lines in the drawing show structure illustrating the design in an environment of use. The broken lines form no part of the claimed design.
